UNITED STATES PATENT OFFICE.

DUANE C. CLARK, OF LINCOLN, NEBRASKA.

TWINE-CUTTER.

1,200,708.

Specification of Letters Patent. Patented Oct. 10, 1916.

Application filed April 17, 1916. Serial No. 91,722.

To all whom it may concern:

Be it known that I, DUANE C. CLARK, a citizen of the United States, residing at Lincoln, in the county of Lancaster and State 5 of Nebraska, have invented a new and useful Twine-Cutter, of which the following is a specification.

The device forming the subject matter of this application is a finger ring provided 10 with means for cutting twine, and the invention aims to improve the cutting blade and to improve the means whereby the blade is assembled with the ring.

With the above and other objects in view 15 which will appear as the description proceeds, the invention resides in the combination and arrangement of parts and in the details of construction hereinafter described and claimed, it being understood that 20 changes in the precise embodiment of the invention herein disclosed, can be made within the scope of what is claimed, without departing from the spirit of the invention.

In the accompanying drawings:—Figure 25 1 shows in top plan, a twine cutter embodying the present invention; Fig. 2 shows the twine cutter in side elevation; Fig. 3 is a section on the line 3—3 of Fig. 1; and Fig. 4 is a plan of the blank out of which the ring 30 is formed.

In carrying out the present invention there is provided a ring 1 equipped at one side with an angle bracket 2 embodying a base 3 and an upstanding arm 4.

35 The invention includes a blade 5 of any desired width and sharpened at its upper edge 25, the blade standing at right angles to the base 3 of the angle bracket 2. The cutting edge is inclined at an angle to the 40 plane defined by the perimeter of the ring at one end of the ring. The blade 5 is equipped at its ends with projecting flanges 6 united by securing elements 7, removably, with the ring 1 and with the arm 4 of the 45 angle bracket 2. To facilitate the cutting

of the twine by the sharpened edge of the blade 5, the blade 5 is disposed at an angle to a diameter of the ring 1, which diameter is disposed at right angles to the arm 4. Since the blade 5 is removable, a dull blade may be 50 replaced readily by a sharp one.

Preferably, but not of necessity, the ring 1 and the angle bracket 2 are fashioned out of a metal blank 8 in the form of a strip, the blank 8 being provided intermediate its ends 55 with a lateral extension 9, the edges 10 of which converge toward each other and merge into a rounded end edge 11. The blank 8 is bent into annular form and its ends are connected as shown at 12, by solder or otherwise, the extension 9 being bent to form the bracket 2, including the base 3 and the upstanding arm 4.

Having thus described the invention, what 65 is claimed is:—

1. In a twine cutter, a finger ring having an outstanding angle bracket including a base and an upstanding arm; a cutting blade having terminal flanges; and securing elements uniting the flanges, detachably, with 70 the arm and with the ring.

2. In a twine cutter, a finger ring provided with an outstanding angle bracket including a base and an upstanding arm; a blade supported on the base and provided 75 with terminal flanges coacting with the ring and with the arm, the blade being disposed at an acute angle to the diameter of the ring, said diameter of the ring being at right angles to the arm; and securing elements 80 uniting the flanges, respectively, with the arm and with the ring.

In testimony that I claim the foregoing as my own, I have hereto affixed my signature in the presence of two witnesses.

DUANE C. CLARK.

Witnesses:

JOHN M. ANDERSON,
EMERY L. FULLERTON.
